CLAIM

We claim ornamental design for a desk, as shown and described.

DESCRIPTION

FIG. 1 is a top view of the desk;

FIG. 2 is a bottom view thereof;

FIG. 3 is a left side view thereof;

FIG. 4 is a right side view thereof;

FIG. 5 is a front view thereof;

FIG. 6 is a rear view thereof; and,

FIG. 7 is a perspective view thereof.

The broken line portion of the figure drawings is included to show environment that forms no part of the claimed design.
